 METHOD FOR REDUCING SLUDGE DEPOSITION
OF FUEL OILS

Robert Greatorex and Demetrios Theodore Emmanuel Zalichi, Sunbury-on-Thames, and William Arthur Partridge, London, England, assignors to The British Petroleum Company Limited, London, England, a British joint-stock corporation

6 Claims. (Cl. 208—177)

Residual fuel oils, i.e. fuel oils consisting of or containing petroleum residues, have a tendency to deposit a waxy sludge on storage and in certain circumstances this can cause difficulties, e.g. where in use the fuel oil has to be passed through a screen or strainer. Such difficulties arise mainly with fuels of Class E, British Standards Specification No. 2869:1957, which are intended to be handled in unheated storage.

We have now found a method whereby this tendency to deposit a sludge can be reduced, without any significant adverse effect on other desirable properties of the oil, such as pour point and viscosity.

The invention consists in chilling a residual fuel oil from an upper temperature of at least 110° F., preferably at least 120° F., especially at least 140° F., to a lower temperature not higher than 90° F., preferably not higher than 70° F., at a rate of at least 0.1° F., preferably at least 1° F., per minute.

Residual fuel oils are normally prepared by blending residual materials from distillation and cracking processes and materials discarded during the production of lubricating oils, with lighter components, such as kerosene or gas oil. This blending is carried out at an elevated temperature, usually of the order of 140° F. or higher. Where, therefore, the method of the invention is to be applied to fuel oils which have just been blended, it will not normally be necessary to pre-heat them.

The chilling may be conveniently effected by passing the fuel oil through conventional heat exchanging equipment, cooled by a flow of cold water or other suitably available cold fluid.

A number of examples of the invention will now be described.

EXAMPLE 1

A fuel oil (A) having a Redwood I viscosity at 100° F. of 199 seconds and a pour point of 15° F. was used in this example. When fuel oil A was cooled at a slower rate than 0.1° F. per minute a waxy deposit or sludge was subsequently deposited and the fuel oil was not filterable. Samples of the same fuel oil when cooled according to the method of the invention were filterable and remained so after a prolonged storage at ambient temperature. The results of these experiments are summarised in Table I

Table I

Cooling rate	Cooling range °F.		Total storage period weeks	Filtration test	Pour point °F.	Kinematic viscosity at 70° F. cs.
	From	To				
(1) <0.1° F./minute	140	60	8	Not filterable.	15	136.7
(2) 12° F./minute	130	60	13	Filterable	0	141.9
(3) 12° F./minute	140	60	13	do	5	141.3
(4) 12° F./minute	180	90	18	do	-15	143.3
(5) 1° F./minute	120	30	-----	do	-----	-----

It can be seen from the above results that the pour point of the oil will be no worse, and indeed may be improved, by chilling the fuel oil according to the meth-

2

od of the invention and that the chilling causes no significant change in the viscosity of the oil.

The above example was carried out in the laboratory. Examples 2, 3 and 4 below were carried out in a pilot plant consisting of a 5 gallon oil reservoir connected via a 0-600 gallon/hour variable stroke pump to a cooling coil encased in a 40 gallon drum with a return to the feed reservoir. A ½" pipe was used throughout and the cooling coil was 18' arranged in four full turns. The oil to be treated was placed in the reservoir and the 40 gallon drum was filled with a suitable cooling medium such as cold water. The oil in the reservoir was heated by an immersion heater to the required upper temperature and the oil was circulated round the system. The cooling rate, as measured by the temperature drop in the reservoir, was adjusted by varying either the oil level in the reservoir, the circulation rate, or the cooling medium temperature.

EXAMPLE 2

In this example another fuel oil (B) was used having a Redwood I viscosity at 100° F. or 214 seconds and a pour point of 25° F. This fuel oil did not pass the filtration test. When cooled at a rate slower than 0.1° F. per minute the filterability of the oil remained poor and a waxy sludge was deposited. Samples of fuel oil B were chilled from 110° F. to 90° F. at rates of 1° F. and 7° F. per minute. The chilled samples were filterable, contained no sludge and showed no significant change in viscosity or pour point after storage at ambient temperature for 16 weeks. The results are summarised in Table II.

Table II

40	Heat treatment of fuel oil B			Filtration test	Sludge	Kinematic viscosity at 70° F. cs.	Pour point °F.
	Cooling range °F.	Cooling rate °F./minute	Storage time weeks				
120-65	<0.1	16	Not filterable	do	Present	111	25
110-90	1	16	Filterable	do	None	114.4	30
110-90	7	16	do	do	do	112.8	10

45

EXAMPLE 3

In this example another fuel oil (C) was used having a Redwood I viscosity at 100° F. of 201 seconds and a pour point of 20° F. Fuel oil C failed the filtration test. Samples of the fuel oil were chilled at various rates between 0.1° and 7° F. per minute. The results of this treatment are given in Table III.

Table III

60	Heat treatment of fuel oil C			Filtration test	Sludge
	Cooling range °F.	Cooling rate °F./minute	Storage time weeks		
150-80	0.4	15	Not filterable	do	Present
150-90	0.6	16	Filterable	do	None
135-90	0.1	5	do	do	Present
150-90	0.1	5	do	do	Do
135-90	1.0	15	do	do	None
150-90	5.8	16	do	do	Do
150-90	1.0	16	do	do	Do
150-90	6.8	16	do	do	Do

It will be seen that the treatment according to the invention in all cases resulted in an improvement in the filterability of the fuel oil although chilling rates below 1° F. did not always prevent sludge deposition. Con-

sequently, rates of 1° F. per minute or faster are to be preferred.

EXAMPLE 4

In this example a fuel oil (D) was used having a viscosity at 100° F., of 212 seconds Redwood I and a pour point of 25° F. The results of the treatment are given in Table IV.

Table IV

Heat treatment of fuel oil D			Filtration test	Sludge	Kinematic viscosity at 70° F. cs.	Pour point $^{\circ}$ F.
Cooling range $^{\circ}$ F.	Cooling rate $^{\circ}$ F./minute	Storage time weeks				
120-65	<0.1	6	Not filterable	Present	115.8	25
150-80	1	3	do	None	117.4	0
150-80	6	6	Filterable	do	121.4	-5

EXAMPLE 5

Storage in all the above examples was at a temperature of $65 \pm 5^{\circ}$ F. Parallel work has been carried out on samples stored under conditions of varying temperature in the range 40° F.- 95° F. to provide a more rigorous test of stability. The results are given in Table V below.

Table V

Fuel oil	Heat treatment			Filtration test	Sludge	Kinematic viscosity at 70° F. cs.	Pour point $^{\circ}$ F.
	Cooling range $^{\circ}$ F.	Cooling rate $^{\circ}$ F./minute	Storage time weeks				
B			16	Not filterable		111	25
B	110-90	1	16	Filterable	None	119.6	30
B	110-90	7	16	do	do	120	30
D			6	Not filterable		115.8	25
D	150-80	1	6	Filterable	None	117.4	0
D	150-80	6	6	do	do	121.8	0
D	150-80	1	16	do	do		
D	150-80	6	16	do	do		

The filtration test referred to in the above examples was carried out as follows:

The oil was forced under a constant pressure of 5 p.s.i. and at a constant temperature in the region of $65 \pm 5^{\circ}$ F. through a filter element of 1 cm. diameter, consisting of 10 layers of 200 mesh wire gauze. The times taken for

80 ml. and 160 ml. of the oil to flow through the filter were measured, and the ratio of times,

$$\frac{\text{Time of flow of 160 ml.}}{\text{Time of flow of 80 ml.}},$$

compared with the ratio of volumes,

$$\frac{160}{80} = 2.$$

The conditions of the test are such that any reduction in the rate of flow of the oil through the filter is due to the filter blocking propensities of the oil. Therefore a time ratio of 2 indicates that the oil was filterable whereas a time ratio substantially greater than 2 or the complete cessation of oil flow through the filter indicates that the oil was not filterable.

The determination of pour points according to IP 15/55 and of viscosities by IP 70/57 or 71/58 entails preheating the samples to 115° F. and 212° F. respectively. As this procedure might destroy the effects of chilling, the determinations in the above examples were carried out without preliminary heat treatment.

We claim:

1. A method of reducing the tendency of a residual fuel oil to deposit a waxy sludge on storage, which consists in chilling the residual fuel oil from an upper temperature of at least 110° F. to a lower temperature not higher than 90° F., at a rate of at least 0.1° F. per minute.
2. A method according to claim 1, in which the rate of chilling is at least 1° F. per minute.
3. A method according to claim 1, in which the upper temperature is at least 120° F.
4. A method according to claim 3, in which the upper temperature is at least 140° F.
5. A method according to claim 1, in which the lower temperature is not higher than 70° F.
6. A method according to claim 1, in which the chilling is effected by passing the fuel oil through heat exchanging equipment chilled by a flow of cold liquid.
